UNITED STATES PATENT OFFICE

134,675

DESIGN FOR A COMBINATION ENVELOPE AND WRITING PAPER

Charles C. Dill, Levelland, Tex., assignor of one-eighth to Ruth Wiley and one-eighth to Max Wiley, both of Wheeler, Tex.

Application June 12, 1942, Serial No. 107,184

Term of patent 3½ years

To all whom it may concern:

Be it known, that I, Charles C. Dill, a citizen of the United States, residing at Levelland, in the county of Hockley and State of Texas, have invented a new, original, and ornamental Design for a combination Envelope and Writing Paper, of which the following is a specification, reference being had to the accompanying drawings, forming a part thereof.

Figure 1 is a plan view of one side of a combination envelope and writing paper prior to folding thereof and showing my new design;

Fig. 2 is a plan view of the opposite side thereof;

Fig. 3 is a plan view of the front of the combination envelope and writing paper shown in Fig. 1, in folded position;

Fig. 4 is a plan view of the opposite side thereof.

I claim:

The ornamental design for a combination envelope and writing paper, as shown.

CHARLES C. DILL.
